AUTOMOTIVE VEHICLE WHEEL LOCK

Frederick O. Gibbons, Whittier, Calif., assignor to Orion Industries, Inc., Los Angeles, Calif.

Filed Aug. 14, 1972, Ser. No. 280,711

Term of patent 14 years

Int. Cl. D8—07

U.S. Cl. D8—113

FIG.1

FIG.2

FIG.3

FIG.5

FIG.4

FIG. 1 is a perspective view of an automotive vehicle wheel lock device showing my new design;

FIG. 2 is a front elevational view of said device;

FIG. 3 is a bottom view of said device;

FIG. 4 is a top view of said device and

FIG. 5 is a top view of a modified form of said device, with said modified form of device having the same appearance shown in FIGS. 1, 2, and 3.

I claim:

The ornamental design for an automotive vehicle wheel lock, substantially as shown and described.
